UNITED STATES PATENT OFFICE.

JOHN H. ELWARD, OF ST. PAUL, MINNESOTA.

IMPROVEMENT IN MOWING-MACHINES.

Specification forming part of Letters Patent No. 154,232, dated August 18, 1874; application filed July 2, 1874.

To all whom it may concern:

Be it known that I, JOHN H. ELWARD, of St. Paul, county of Ramsey, State of Minnesota, have invented a new and useful Improvement in Grass-Harvesters, of which the following is a full, clear, and exact description, reference being had to the accompanying drawings, making part of this specification, in which—

Figure 1 represents a perspective view of my improved mower, and Fig. 2 is a side elevation of the same with the inner drive-wheel removed.

Similar letters of reference denote corresponding parts in both figures.

The invention relates to a novel construction of the main frame and drooping shoe of the machine, and to the manner of combining the driving and carrying wheels therewith, whereby, while the frame is free to vibrate to permit the cutting apparatus to follow the undulations in the surface of the ground, it is at the same time, when in operation, maintained in a position substantially parallel with the surface of the ground over which it is drawn, as hereinafter explained. It further relates to a novel arrangement of the seat and lifting-lever relatively to the main frame and hinged tongue, whereby the weight of the attendant is made to tilt the frame and raise the cutting apparatus for passing an obstruction, without throwing the weight of such cutting apparatus upon the tongue, and thence upon the neck-yoke of the team, as hereinafter explained.

In the accompanying drawing, A represents the main axle and main transverse frame-bar, provided at each end with a journal, upon which the main drive-wheels B B are mounted. To this bar A, projecting in rear thereof, and either cast with said bar or rigidly united thereto, is a rectangular frame composed, aside from the bar A, of the longitudinal side bars A¹ A² and the rear transverse bar A^x, the longitudinal bars A¹ A² being provided with transverse arms or brackets a, having vertical ears, which afford bearings for the counter or pinion and bevel-wheel shaft C; pinions e on the ends of which, and which may be connected with said shaft by backing-ratchets, engage with and are driven by spur-wheels b, attached to the driving-wheels B. The inner longitud-

inal bar A² extends forward of the axle-bar in advance of the driving-wheels, and has formed upon or rigidly connected with it a drooping runner or shoe plate, D, said plate joining the bar A² at its front and rear, and drooping between these points to, or nearly to, the plane on which the driving-wheels B rest, where it is expanded in width at a point in advance of the inner drive-wheel, to form the shoe, the support for the inner hinged end of the finger-bar, and a shield for protecting the crank-wheel and pitman from the grass. The plate D in rear of the finger-bar and the shoe part rises vertically, or nearly so, at d, sufficiently far to afford a support for the forward lower end of the inclined crank-shaft, which passes through a tubular bearing therein. The plate D is then curved or turned backward again, passing above the crank-shaft and underneath the axle-bar to the rear end of bar A, to which it is united, a vertical lug or ear, d', formed upon or attached to it near its rear end, affording a rear bearing for the crank-shaft. The inner end of the finger-bar is provided with perforated uprights or ears e, the rear one of which surrounds the crank-shaft, and is supported upon a forward sleeve-extension of the tubular bearing therefor at d, and the forward one is pivoted in line with the crank-shaft in an upright, e, formed upon or attached to the shoe in such manner as to permit the finger-bar to be turned up from a horizontal to a vertical position, and vice versa, turning around the crank-shaft as a center. To the frame-bar A, about in the same transverse plane with the finger-bar, is connected a carrying-wheel, B', made, by preference, of about the same diameter as the driving-wheels B, in such manner that its stub-axle may be connected directly to the bar A² and made to support the forward end of said bar at the same height from the ground with the rest of the frame. For the purpose of adjustment of the height of the shoe from the ground, for transportation or other purpose, the axle of wheel B' is secured to a vertical plate or standard, F, provided with a number of horizontal flanges, f, any one of which may be bolted to the frame-bar A², for setting the forward end of said bar and the shoe and cutting apparatus connected therewith at the desired height.

G is the tongue, hinged at its rear end, through bounds or a branching tongue plate or iron, g, to the axle and frame-bar A; and H is the seat-plank, rigidly secured to the rear end of the tongue, and extending therefrom to the rear and upward over the rear frame-bar A^x, which affords a support for the feet of the driver sitting in seat H'. The seat plank or standard H has an arm or lever, h, rigidly connected with it, at or near midway of its length, said lever extending obliquely from plank to the right-hand side of the seat H', as shown.

By this arrangement of the seat relatively to the vibrating main frame, the driver is enabled, by rising from his seat, to throw his entire weight on the rear bar A^x of said frame, and, by depressing said bar, to raise the forward end of bar A² and the cutting apparatus connected therewith, for passing an obstruction in the way of the cutters, after which, by resuming his seat, the cutters again descend to their proper working position. Where, from any reason, the weight of the driver is insufficient for the purpose of raising the cutting apparatus, the driver standing on bar A^x, by grasping and raising on the arm or lever h, can depress the rear end of the frame and cause the cutters to be raised in a manner that will be readily understood.

The cutting apparatus, hinged within the shoe as above explained, is prevented from dropping below or much below a horizontal position by coming in contact with and resting upon the upper face of the shoe or runner at its inner side; it may, however, be raised at its outer end, for passing an obstruction, or folded into a vertical position against the outer face of bar A², within the path of or between the driving-wheels, by means of a lever, I, pivoted in a vertical flange, I', on the frame

or frame-bar A, and a cord or chain, i, passing from said lever through a perforation in or over a pulley connected with the said frame-bar, and connected with the finger-bar at a point outside its hinge, as shown in Fig. 1. Instead of the usual crank-wrist on the crank-shaft, a disk, K, is employed, provided with two grooves on its vertical face, said grooves crossing each other at right angles in the center of the disk, and the connecting-rod K' has attached to it two pivoted slides, which reciprocate, one in each of said grooves, in such manner as to give two reciprocations of the sickle in each direction to each revolution of the crank-shaft.

Parts of the machine not particularly described may be constructed or applied in any usual or preferred manner.

Having thus described my invention, what I claim as new, and desire to secure by Letters Patent, is—

1. The vibrating main frame A A¹ A² and drooping shoe or runner D, constructed as described, in combination with the forward carrying-wheel B, connected with the forwardly-projecting bar A² in advance of and between the driving-wheels, and in line with the hinged finger-bar, for maintaining the frame in a position parallel with the ground, substantially as specified.

2. The arm or lever h, rigidly connected with the seat-standard, and projecting at the side of the driver's seat, for enabling the driver, when standing on the bar A^x, to tilt the vibrating main frame, substantially as and for the purpose described.

In testimony whereof I have hereunto set my hand this 14th day of May, A. D. 1874.

JOHN H. ELWARD.
